(57) **CLAIM**

The ornamental design for a handle for cleaning tool, as shown and described.

DESCRIPTION

FIG. 1 is a perspective view of the handle for cleaning tool; FIG. 2 is a front elevation view of the handle for cleaning tool shown in FIG. 1;

FIG. 3 is a rear elevation view of the handle for cleaning tool shown in FIG. 1;

FIG. 4 is a right side elevation view of the handle for cleaning tool shown in FIG. 1;

FIG. 5 is a left side elevation view of the handle for cleaning tool shown in FIG. 1;

FIG. 6 is a top plan view of the handle for cleaning tool shown in FIG. 1; and,

FIG. 7 is a bottom plan view of the handle for cleaning tool shown in FIG. 1.

The broken lines represent portions of the handle for cleaning tool that form no part of the claimed design.

1 Claim, 7 Drawing Sheets
